(57) **CLAIM**

The ornamental design for a drink cooler as shown and described.

DESCRIPTION

FIG. 1 is a top back-right perspective view of the drink cooler of the present invention;

FIG. 2 is a top front-right perspective view thereof;

FIG. 3 is a back view thereof;

FIG. 4 is a front view thereof;

FIG. 5 is a right side view thereof;

FIG. 6 is a left side view thereof;

FIG. 7 is a top view thereof;

FIG. 8 is a bottom view thereof;

FIG. 9 is a bottom back-right perspective view thereof; and,

FIG. 10 is a bottom front-right perspective view thereof.

The portions of the drink cooler illustrated in broken lines form no part of the claimed design.

1 Claim, 10 Drawing Sheets
